J. F. LEMONS

SPRAYING DEVICE

Filed April 22, 1920

UNITED STATES PATENT OFFICE.

JOSEPH F. LEMONS, OF CEDAR HILL, TENNESSEE, ASSIGNOR, BY DIRECT AND MESNE ASSIGNMENTS, TO WILLIAM L. PITT, OF CLEVELAND, OHIO.

SPRAYING DEVICE.

Application filed April 22, 1920. Serial No. 375,761.

To all whom it may concern:

Be it known that I, JOSEPH F. LEMONS, a citizen of the United States, residing at Cedar Hill, in the county of Robertson and State of Tennessee, have invented a certain new and useful Improvement in Spraying Devices, of which the following is a full, clear, and exact description, reference being had to the accompanying drawings.

10 This invention relates to spraying devices and more particularly to portable devices of this character which are used for distributing pulverulent material for the purpose of destroying insects and undesirable growths on trees, plants and other vegetable life.

Some of the objects of the present invention are to provide a device of this character which shall be so constructed as to permit 20 the center of gravity thereof to be adjacent the operator, so as to afford perfect balance and ease of manipulation; to provide a device of this character which shall draw the pulverized material into contact with the 25 revolving fan before discharging said powder, thereby securing a uniform distribution of finely divided material; to provide a device of this character which shall be simple in construction and inexpensive 30 to manufacture, while further objects and advantages will appear as the description proceeds.

In the accompanying drawing wherein I have shown an illustrative embodiment of 35 my invention, but without intent to limit myself thereto, Fig. 1 is a perspective view of my device in a position ready for operation; Fig. 2 is a top plan view thereof; and Figs. 3 and 4 are sectional views taken on 40 the lines 3—3 and 4—4, respectively, of Fig. 2.

Describing the various parts by reference characters, 1 indicates a suitable reservoir which is provided at the top thereof with a 45 filling opening 2 which is normally closed by a detachable cover 3. The reservoir 1 is secured to the top cylindrical wall of the rear or open end of a suction pipe 4, and braced thereon by the straps 5—5. An opening 6 communicates with the interior of the suction pipe 4 and the interior of the reservoir 1, the effective size of said opening being varied by means of a rotatable sleeve member 7 which is provided with a slotted 50 opening 8 that may be brought into alignment

with the opening 6 by grasping the rear end of said sleeve and rotating it through the desired angle. An elbow 10 is secured to the forward end of the suction pipe 4 and said elbow communicates with the interior of the vertical fan casing 11 in axial alignment with the fan member 12. The fan member is mounted on a shaft 14, journaled in a strap 15 which extends diametrically across one side of the casing 11 and projects on the forward side thereof as indicated at 16. A small gear 17 is mounted on the outer end of said shaft, intermediate said strap, and a bracket 18, which is fastened to said strap. A second strap 20 is fastened on the opposite side of said casing substantially parallel to the pipe 4 and in such position as to project on the forward side of the casing in transverse alignment with the projection 16. A transverse shaft 21 is journaled in said projections and mounts at one end thereof a drive gear 22 and an operating crank 23, and at the other end a bevel gear 24. A small intermediate gear 25 and a larger gear 26 are fastened together and journaled on a stud shaft mounted on the strap 15, said gears being meshed respectively with the drive gear 22 and the fan gear 20 so that by slowly turning the operating crank 23 the fan will be caused to rotate rapidly and produce a suction in pipe 4 and divert the blast through the discharge nozzle 27 at the top peripheral portion of the fan casing.

The strap 20 has preferably formed integral therewith the spaced lugs 28—28 which rotatably support the forward end of a shaft 29 which extends rearwardly through a bearing plate 30 and into reservoir 1. The forward end of said shaft is fitted with a beveled gear 31 which meshes with the beveled gear 24. The rear end of said shaft is provided with a brush 32 and the agitating members 33—33 positioned on each side thereof, said parts being securely clamped together by the nuts 34—34 threaded on the shaft. The brush is of such diameter as to bring its lower portion in position to sweep over the outlet opening 6, thereby assuring a positive feed of the powder while the rotary agitating members serve to feed the powder into contact with the brush.

In operation, the reservoir 1 is filled with the powder to be sprayed, such as arsenate of lead, and the device swung from the

side of the operator by the strap 35 which is passed over his shoulder and fastened to each end of the device as illustrated in Fig. 1. It will be noted that the reservoir 5 is positioned at the rear, and the fan casing at the front of the operator, so that the center of gravity of the machine is close to the operator's body which permits balance of the device and easy carrying and operating 10 thereof. By turning the crank 23, the fan 12 is caused to rotate rapidly, thereby producing a suction draft through pipe 4, and simultaneously rotating the brush 32 and agitators 33-33, to feed the finely divided 15 powder through openings 6 and 8 in a quantity determined by the position of the rotatable sleeve member 7. The powder is carried forward by the suction draft into the fan casing, and into contact with the 20 revolving fan where any lumps are broken up which might have been drawn therein. The pulverized material is then blown through the discharge nozzle 27 and through any suitable detachable directing devices 25 such as indicated at 36 and 37.

The operator will be advised when the reservoir is about empty by the downward tipping of the forward end of the device and thus refilling of the reservoir can be accomplished before starting off on another expedition and the operator is aware at all 30 times of the approximate quantity of the material at hand.

Having thus described my invention, what 35 I claim is:—

1. A portable device of the class described comprising a casing having an inlet and a discharge opening, a fan member journaled in said casing, means for rotating said fan 40 member, a reservoir, a pipe connecting said reservoir and one of said openings, and means for suspending said device from the operator whereby substantially one-half of the weight of said device will be positioned 45 forwardly and the other half rearwardly of the operator.

2. A portable device of the class described, comprising a casing having an inlet and a discharge opening, a fan member journaled 50 in said casing, a pipe communicating with one of said openings, a reservoir communicating with said pipe, means for rotating said fan to produce an air draft through said pipe, and means for suspending said device 55 from the operator whereby substantially one-half of the weight of said device will be positioned forwardly and the other half rearwardly of the operator.

3. A portable device of the class described, 60 comprising a casing having an inlet and a discharge opening, a fan member journaled in said casing in axial alignment with said inlet opening, a pipe communicating with said inlet opening, a reservoir mounted on 65 said pipe and in communication therewith,

means for driving said fan member, an agitating device journaled in said reservoir, driving connections between said agitating device and said driving means and means for suspending said device from the operator 70 whereby substantially one-half of the weight of said device will be positioned forwardly and the other half rearwardly of the operator.

4. A portable device of the class described, 75 comprising a casing having an inlet and a discharge opening, a reservoir positioned in operative relation to said inlet opening and adapted to discharge its contents therein, means within said casing for discharging 80 said contents through said discharge opening, and means for suspending said device from the operator, said means and the elements of said device being so arranged that substantially one-half of the weight of said 85 device will be positioned forwardly and the other half rearwardly of the operator.

5. A portable device of the class described, 90 comprising a pipe, a reservoir positioned at one end of said pipe and in communication therewith, a fan casing positioned at the opposite end of said pipe and in communication therewith, a fan rotatably journaled in said casing and suspending means fastened to said device whereby said device is positioned forwardly and rearwardly 95 of the operator in a balanced position.

6. A portable device of the class described comprising a pipe communicating at one end thereof with the atmosphere, a reservoir 100 positioned on said pipe and adapted to discharge its contents into said pipe, a fan casing positioned at the opposite end of said pipe and communicating therewith, a fan rotatably journaled in said casing and 105 adapted to create an air draft through said pipe and means for suspending said device whereby the center of gravity thereof shall be substantially adjacent the operator.

7. A portable device of the class described 110 comprising a fan casing having a discharge nozzle in communication with its peripheral portion, a fan rotatably journaled in said casing, means for rotating said fan, a suction pipe in communication with the fan 115 casing through a side wall thereof the opposite end of the pipe being open, a reservoir carried by the open end portion of said pipe and in communication therewith and means for suspending said device whereby the center of gravity thereof shall be adjacent the operator.

8. In a portable device of the character described, the combination with a pipe, of a reservoir positioned in operative relation thereto and in communication therewith, an air blast apparatus in communication with said pipe and adapted to create an air draft therethrough, and means for suspending said device from the operator, said reser-

- voir being adapted to be positioned rearwardly and said air blast apparatus forwardly of the operator to suspend said device in a balanced position from the operator.
9. In a portable device of the character described, the combination with a pipe open at one end and communicating with a fan casing at the other end, of a reservoir mounted on said pipe adjacent the open end and in communication therewith, means for controlling the opening between said reservoir and said pipe, and means for suspending said device in a balanced position from the operator.
10. A powder gun adapted to be supported by the operator and comprising a casing provided with a discharge in communication with the peripheral portion of the casing, fan blades rotatably supported within the casing, a suction pipe in communication with the casing through a side wall thereof, and at a point inwardly of the blades, said suction pipe being also in communication with the atmosphere, a reservoir mounted upon said suction pipe and in communication therewith at a point inwardly of the communication of the suction
11. A portable device of the character described comprising a reservoir and an air blast apparatus interconnected by a conduit, an operating crank for said air blast apparatus, and means for suspending said device from the operator, said means being so connected to said device that said conduit will be positioned alongside the operator with said reservoir rearwardly and said air blast apparatus and operating crank forwardly of the operator.
12. A portable device of the character described comprising a fan casing having a discharge nozzle in communication with its peripheral portion, a fan journaled in said casing, a conduit having one end thereof open to the atmosphere and the other end communicating with said casing in axial alignment with said fan, and a reservoir communicating with said conduit and adapted to discharge its contents therein.

In testimony whereof, I hereunto affix my signature.

JOSEPH F. LEMONS.
